[57] ABSTRACT

An electric or electronic timepiece is provided with a mechanical regulating member coordinately actuated with a switch so that driving current for the electro-mechanical transducer of the timepiece is cut off before operative engagement by said regulating member and is not restored until after said regulating member is disengaged.

4 Claims, 2 Drawing Figures

FIG. 1

PATENTED SEP 12 1972

3,690,058

SHEET 2 OF 2

FIG.2

ELECTRIC OR ELECTRONIC TIMEPIECE

BACKGROUND OF THE INVENTION

This invention relates to an electric or electronic watch having a second hand regulating device. In such watches, a switch is generally provided for disconnecting the battery voltage source or a part of the driving circuit of the electro-mechanical transducer of the timepiece when the second hand is regulated and to permit adjustment of the driving signal.

SUMMARY OF THE INVENTION

Generally speaking, in accordance with the invention, an electric or electronic timepiece is provided wherein the timing of the second hand is regulated mechanically coordinate with the application or cutting off of driving current to an electro-mechanical transducer. Regulation of the second hand is achieved by a mechanical regulating member which engages a portion of the time train of the timepiece, while switch means is provided for controlling the application of driving current to said electro-mechanical transducer. Regulation of the second hand is achieved by a mechanical regulating member which engages a portion of the time train of the timepiece, while switch means is provided for controlling the application of driving current to said electro-mechanical transducer. The means for coordinately operating said switch means and said regulating member is adapted to cut off the current to said electro-mechanical transducer before operative engagement between said regulating member and said time train, and to disengage said regulating member from said time train before said driving current is reapplied to said electro-mechanical transducer.

BRIEF DESCRIPTION OF THE DRAWINGS

For a fuller understanding of the invention, reference is had to the following description taken in connection with the accompanying drawings, in which:

FIG. 1 is a block diagram of an electronic watch according to the invention; and

FIG. 2 is a plan view of the important parts of said watch.

DESCRIPTION OF THE PREFERRED EMBODIMENTS

FIG. 1 shows a diagram of an electronic watch having a battery 1 as the driving source. The accuracy of timekeeping is determined by a crystal oscillator 2. An electric signal produced by crystal oscillator 2 and an oscillating circuit 3 is divided by a divider circuit 4. Pulse signal 17 thus produced is sent as a driving signal to driving coil 5, which is connected to the stators 6 and 6' of a step motor, which serves as an electro-mechanical transducer. The rotor 7 of said step motor, formed from permanent magnets having alternating north and south poles, is intermittently rotated at a rate of one pole per second in response to the pulse signal applied to driving coil 5. This rotation is transmitted to the time train of the timepiece through seconds wheel 8 by means of pinion 15 depicted in FIG. 2. Pinion 15 is mounted coaxially with the rotor of said step motor, the second hand being adapted to move one second in response to a one-pole rotation of the rotor.

As shown in FIG. 2, this timepiece is provided with a reset switch 9 electrically connected with a divider circuit 4 for controlling the application of the driving pulse signal 17 to driving coil 5. This reset switch is set as follows:

By pushing and pulling on stem 13, a regulating transmitting lever 11, mounted coaxially on setting lever pin 12, rotates about the axis of setting lever pin 12. The rotation of regulating transmitting lever 11 operates regulating lever 10 and alternately shortcircuits and disconnects contact point 9A of reset switch 9 with contact portion 11A of said regulating transmitting lever. Thus, said regulating transmitting lever has two functions. One is its use as a substitute for the contact of the reset switch, while the other is the operation of regulating lever 10.

At the normal position of stem 13, as shown in full lines in FIG. 2, regulating transmitting lever 11 positions regulating lever 10 in the position shown in full lines, at which regulating portion 10C is out of engagement with regulating cam 14. Further, said regulating transmitting lever is out of engagement with reset switch 9, also as shown in full lines.

When the stem is pulled a first incremental distance as represented by the phantom line showing of reset switch 9', regulating lever 10' and regulating transmitting lever 11', the contact portion 11A of said regulating transmitting lever engages and is shortcircuited with contact point 9A of reset switch 9. At this point, while regulating lever 10 is pivoted slightly about pin 16 to the position 10', regulating portion 10C thereof is still out of engagement with regulating cam 14.

When stem 13 has been pulled a second further incremental distance to the dashed line showing of reset switch 9'', regulating lever 10'', and regulating transmitting lever 11'', contact point 9A of reset switch 9 remains shortcircuited (engaged with regulating transmitting lever 11), while the regulating portion 10C of regulating lever 10 engages regulating cam 14 to mechanically regulate rotor 7.

If stem 13 is pushed inwardly a first incremental distance to the point represented by the phantom line showings of reset switch 9', regulating lever 10', and regulating transmitting lever 11', from the outer position shown by dashed lines, the engaging portion 11B of the regulating transmitting lever engages against surface 10B of regulating lever 10 to raise said surface and rotate the regulating lever 10 in the counterclockwise direction about pin 16 as viewed in FIG. 2. As a result of this movement, regulating portion 10C of said regulating lever is disengaged from regulating cam 14 while contact portion 11A of regulating transmitting lever 11 remains shortcircuited with contact point 9A of the reset switch, so that the driving signal is not supplied to driving coil 5 and so that the electro-mechanical transducer is not operated, portion

When stem 13 is pushed inwardly to the initial position shown in full lines, engaging portion 11B of regulating transmitting lever 11 is disengaged from surface 10B of regulating lever 10. Instead, surface 11C of said regulating transmitting lever engages portion 10A of said regulating lever to rotate said regulating lever about the axis defined by pin 16 to the initial full-lined position. At this position, the regulating transmitting lever is out of engagement with reset switch 9 to cause divider circuit 4 to become operational. At this instant, a driving signal 17 is supplied to driving coil 5 and the rotor starts to rotate. Portion 10A of regulating lever 10 is formed with a surface defining a circular arc corresponding to the circular arc defined by surface 11C of the regulating transmitting lever.

Thus, in the arrangement in accordance with the invention, regulating lever 10 is disengaged from regulating cam 14 before reset switch 9 is released to permit the application of driving current to the step motor. Similarly, the reset switch is shortcircuited before regulating lever 10 engages the regulating cam, so as to ensure that the regulating cam has come to a stop before such engagement.

On the other hand, if the reset switch and regulating lever are not so coordinated, it is possible for regulating portion 10C to be in the path of regulating cam 14 while said regulating cam is rotating, thereby causing mechanical interference, which tends to delay starting time. This is especially the case in electric or electronic timepieces having second hands which are moved intermittently. In such timepieces, the member to be regulated is interfered with by the regulating member for the period of one driving pulse, so that one or a half second is lost, thereby making it difficult to set the second hand to a standard time, and obviating the provision of the regulating means.

What is claimed is:

1. An electric or electronic timepiece comprising an electro-mechanical transducer including an electrical driving portion and a mechanical driven portion; a time train including and driven by said mechanical portion of said electro-mechanical transducer; a driving circuit for applying a driving signal to said electrical portion of said electro-mechanical transducer; mechanical regulating means for displacement between at least a first position in interfering relation with a portion of said time train for regulating said time train and a second position out of interfering relation with said time train; switch means positionable in a first state at which said driving signal is applied to said electrical portion of said electro-mechanical transducer and a second state at which said driving signal is not so applied; and means for coordinately actuating said switch means and regulating means so that said regulating means is displaced from its first position to its second position before said switch means is switched from its second state to its first state and so that said regulating means is displaced from its second position to its first position after said switch means is switched from its first state to its 45

second state, whereby said regulating means does not interfere with the moving time train.

2. An electric or electronic watch as recited in claim 1, wherein said electro-mechanical transducer is a step motor, said electrical driving portion being a driving coil, said mechanical driven portion being a rotor, said time train including a regulating cam for cooperative engagement with said regulating means.
3. An electric or electronic timepiece as recited in claim 1, wherein said coordinate actuating means includes a pivotably mounted regulating transmitting lever, said regulating means includes a regulating lever positioned for rotation in response to the rotation of said regulating transmitting lever, and said switch means includes a switch contact positioned in the path of rotation of said regulating transmitting lever, the pivotable rotation of said regulating transmitting lever in a first direction by a first incremental distance pivoting said regulating lever from said second position to a third intermediate position out of interfering relation with said time train and engaging said transmitting regulating lever against said switch contact to place said switch means in said second state, the incremental rotation of said transmitting regulating lever in said first direction a second incremental distance serving to displace said regulating lever into said first position while maintaining contact with said switch contact to maintain said switch means in said second state, the step-wise incremental rotation of said transmitting regulating lever in a second direction opposite to said first direction serving to first position said regulating lever in said third intermediate position while maintaining engagement of said transmitting regulating lever with said switch contact after a first incremental displacement and then disengaging said transmitting regulating lever from said switch contact and positioning said regulating member in said second position after a second further incremental displacement in said second direction.

- 40 4. An electric or electronic timepiece as recited in claim 3, including a stem projecting outside of said timepiece, the pivotable rotation of said regulating transmitting lever being in response to the longitudinal displacement of said stem.
